METHOD OF AND APPARATUS FOR CONTINUOUS FLOW DENSIFIERS

Raymond F. Mitten, Cleveland, Ohio, assignor to
 The Yoder Company, Cleveland, Ohio, a corporation of Ohio

Application March 25, 1948, Serial No. 17,088

10 Claims. (Cl. 259—146)

1

This invention relates to a continuous flow densifying method and apparatus, especially to an apparatus and method for use in feeding aggregates to continuous concrete mixers wherein such aggregates are fed at a constant rate dependent upon the dry weight of such aggregates, although the present invention is also applicable to other fields, such as control of the mixture of foundry sand and binders.

In previous manufacturing of concrete by batch processes, it is common practice to proportion cement and aggregates by weight, or by volume in the manufacture of concrete and concrete products. Proportioning by weight involves the use of complicated and costly batch weighing equipment that requires considerable man-power for its operation. Recently the concrete industry has been changing over to continuous type of concrete mixers wherein the ingredients are continuously fed into the mixer at one portion thereof and continuously discharged from another portion of the mixer. When using continuous mixers for concrete, it is possible to feed the mixers by weight proportioning only through the use of costly, bulky, complicated constant weight feeding devices. Then too, some continuous mixers are fed by volume of aggregates, but as the volume of various aggregates change due to moisture content, the relation between the aggregate and Portland cement varies greatly and consequently undesirably alters the properties of the concrete produced. These devices have operated upon various principles, but have in all instances, been complex mechanisms that are objectionable, both because of their original cost and because of their maintenance required on such devices to keep them operating satisfactorily. Of course, with expansion of the concrete industry and with the use of new types of aggregates, larger continuous mixers are being used today and these mixers, and any constant weight feeders provided therefor, have had proportioned increases in maintenance and power costs.

The continuous type of concrete mixer has established itself as a very satisfactory piece of apparatus that produces a desired quality of mix with low power and maintenance cost per cubic yard of material produced. Also the initial cost has not been excessive with the exception of the relatively complex, sensitive constant weight feeder device used.

As indicated hereinbefore, it has been known that the various aggregates used in concrete manufacture, such as sand, gravel, slag, cinders,

2

haydite, or other fine or loose material varies in volume with the amount of water present in the aggregate. Thus the use of any constant volume type of feeder for a continuous mixer is not accurate since varying amounts of the aggregate would be delivered dependent upon the moisture content of same. It has been satisfactory to use constant weight feeder devices because the weight of the water present in the aggregate has not upset the desired ratios, or proportions of the aggregates to the other components of the concrete being produced. The moisture content of an aggregate may vary from approximately 0% moisture up to as high as about 20% moisture content, since higher moisture contents usually render the aggregate undesirable for use until it has been reduced to a lower moisture content.

The general object of the present invention is to provide an apparatus and method for use in continuously supplying constant weight quantities of aggregate, based on the dry aggregate present, regardless of the moisture content and original volume of such aggregate.

Another object of the invention is to reduce any aggregate to a standard volume regardless of the moisture content of same.

Another object of the invention is to provide inexpensive, sturdy apparatus for continuously withdrawing a constant volume of aggregate from a storage hopper.

A further object of the invention is to densify material in a storage hopper so as to permit uniform discharge of effective dry weights of such material.

Attention is directed to the accompanying drawings, wherein:

Fig. 1 is a side elevation, partially in section, of apparatus of the invention; and

Fig. 2 is a fragmental vertical section taken on line 2—2 of Fig. 1.

Throughout the specification and drawings, similar reference characters will be used to refer to the same parts for ease of identification of same.

The present invention, broadly speaking, in the method disclosed herein, resides in the fact that I have discovered that aggregate materials of varying moisture contents can be reduced to uniform volumes of material by vibrating such material. The apparatus of the invention broadly comprises the use of a hopper having an open bottom section, a moving belt positioned immediately below the discharge section of the hopper, and at least partially supporting the contents of

the hopper, and a vibratory plate member associated with the belt and adapted to transmit vibrations through the belt to material in the hopper.

Reference is now made to the accompanying drawings, wherein Fig. 1 indicates a continuous flow densifier 10 which includes a conventional hopper 11 that has an open lower end or discharge section provided therefor. An aggregate material 12 is contained in the hopper and is fed thereto in any desired manner, either continuously or intermittently as required. The hopper 11 is supported by braces 13. The aggregate 12 contained in the hopper 11 is adapted to be at least partially supported by means of an endless belt 14, as one feature of the invention. This endless belt 14 is formed from any desired material, such as a rubber-fabric composition, and the belt 14 is positioned by means of two drums 15 and 16 which are in spaced relation with the belt 14 being substantially horizontally positioned thereby for movement immediately below the discharge portion of the hopper 11. Any conventional means, not shown, may be provided for driving one of the drums 15 or 16 so that the belt can be rotated at a convenient speed. The hopper 11 has a vertically adjustable discharge gate 17 slidably positioned on one side thereof and the belt 14 is placed with relation to the hopper 11 so that the belt moves outwardly of the hopper in passing gate 17 so that aggregate 12 can be carried from the hopper on the belt, as indicated.

In order to vibrate the aggregate 12 while it is in or passing through the hopper 11, a plate 18 is positioned immediately under the top stretch or section of the belt 14. This plate 18 may be formed from any desired material, usually metal, that it is of substantially the same size as the lower portion of the hopper 11. The plate 18 carries a downwardly extending bracket 19 formed to receive a transversely directed shaft 21. The shaft 21 is smaller in diameter than the holes 22 provided in the bracket 19 for receiving the shaft 21. Thus an eccentric sleeve 23 can be secured to the shaft 21 by a key 24 whereby the eccentric sleeve 23 will rotate integrally with the shaft 21 and occasion vibratory vertical movement of the plate 18 as the shaft 21 is rotated. Any conventional means may drive the shaft 21 and an electric motor 25 is provided for this purpose. It will be realized that the desired vibration of the plate 21 may be effected in any desired manner and the vibration may have transverse as well as vertical components, or it may even comprise oscillations in a substantially horizontal plane.

The bracket 19 is loosely confined by means of box-like structure 26 that is supported on a frame 27 by means of brackets 28 so that movement of the plate 18 and associated means are limited and a safety device is provided, should the driving support means for the plate 18 fail.

The construction and arrangement of the plate 18 is such that vibration thereof is transmitted through the belt 14 to the contents of the hopper 11. The size of the hopper 11 and the amount of aggregate material therein is so regulated that the aggregate material is subjected to a sufficient length of vibration as to reduce its volume to a constant figure which will not change with extended vibration thereof whereby removal of a constant volume of aggregate from the hopper will withdraw, in dry weight, a constant weight of the aggregate. This constant weight of aggregate

withdrawn, is, it will be seen, free from and not dependent upon the amount of moisture content of such aggregate. As previously indicated, the amount of moisture in the aggregate does not interfere materially in the proportioning of a concrete mix, but it is important that constant dry weights of material be supplied.

In tests conducted upon a slag blend aggregate which was composed of expanded blast furnace slag combined with fine hard slag, it was determined that a test sample contained 12½% moisture when a sample of such material was thoroughly dried. By measuring the volume of the sample before and after drying, it was established that the sample had a shrinkage in volume of 27.2%. Vibration of the dry sample effected a relatively rapid further shrinkage of 2.8% so that the wet sample when dried and vibrated had shrunk a total of 30%. A second sample of the same material, when treated in its original, wet condition, by vibrating same in a suitable container, had its volume reduced 30% so that the vibrated, wet sample had identical volume with the corresponding amount of the original sample that had been dried and then vibrated. Addition of 12½% moisture to the dried sample of aggregate resulted in a bulking or increase in volume of over 40% of the dry volume of such material so that the bulked, dried sample returned to its original volume.

In another test upon the slag blend aggregate referred to hereinbefore, the aggregate was thoroughly dried and moisture additions of 4%, 8%, 12%, and 16% were added to test quantities. Bulking, or volumetric increase occurred in the samples in proportional amount to the percentage of water added thereto. However, when the moistened test aggregates were vibrated they rapidly assumed uniform volumes regardless of the moisture content of same or their previous volumes when wet and unvibrated.

In another instance tests were conducted upon fine sand which had a smaller content of fine gravel. The tested specimen was dried and then 45 8½% of water was added to the sample and thoroughly mixed therewith, which water caused the sample to become slightly gummy. A portion of the aggregate was vibrated and there was a 34% loss in volume. A second portion of the wet aggregate material was dried and the dried aggregate vibrated for a short time with the total final loss in volume of the second aggregate specimen being 34%.

In another test made upon cinders, it was determined that the cinders being tested contained 10% moisture. Corresponding samples of the cinders showed a loss of 34½% in volume, both by a vibrating action and by a combined drying and vibrating action.

In view of the foregoing and other test results, it has been established that a constant volume feeder method can be used for feeding constant weights of aggregate material where one is considering the dry weights of such aggregate material and the variable water content of same is ignored. Hence the total weight of aggregate feed will vary dependent upon the moisture content of the material but predetermined amounts of aggregates, based on the dry weight of same, can be continuously and accurately mixed by the method of the invention. Thus improved mixing is effected by the invention since it overcomes the disadvantages of both the previous constant weight and constant volume feeder devices.

It will be realized that in some instances it may be desirable to use other types of vibrating means than that disclosed herein, and one example of such alternate means could be a vibratory support and discharge plate that would be substituted for the belt 14, plate 18 and associated means. Such vibratory support would be associated with the hopper so that, preferably, the densifying action would be completed prior to passage of the material from the hopper. Any desired siding devices may be used with or be placed on the belt 14 to aid in holding material thereon.

While a complete embodiment of the invention has been illustrated and described in detail herein, it will be realized that the invention is not limited to the specific example set forth since modification may be resorted to within the scope of the appended claims.

Having thus described my invention, what I claim is:

1. That method of making the volume of an aggregate, that expands as its moisture content increases, uniform regardless of the moisture content of same comprising the steps of vibrating a mass of the aggregate to condense same to a uniform volume regardless of the moisture content of same, and continuously withdrawing a constant volume of aggregate.

2. A method of continuously discharging a uniform quantity of an aggregate regardless of the moisture content of same comprising the steps of vibrating a quantity of the material to render the volume thereof uniform regardless of the moisture content of same, and feeding a constant dry weight of the material continuously from the original quantity of same by volumetrically controlling the amount of material discharged.

3. A continuous dispenser device for granular aggregate material comprising a hopper for storing the material, said hopper having an open lower end, an endless belt, a pair of spaced drum means journaling said belt with the top portion thereof being substantially horizontal and immediately below the lower end of said hopper, said belt being adapted to support the contents of said hopper, means for rotating at least one of said drum means for rotating said belt, said hopper having an adjustable discharge gate on one side of the lower portion thereof, a support plate positioned immediately below the top portion of said belt and in contact with the lower surface of same, said plate being positioned directly below the lower end of said hopper, and means for vibrating said plate associated therewith whereby material in said hopper and supported on said belt will be agitated and can be continuously discharged from said hopper by movement of said belt.

4. A continuous dispenser device for granular material comprising a hopper for storing a quantity of the material, said hopper having an open lower end, an endless belt, means journaling said belt with the top portion thereof being immediately below the lower end of said hopper to support the contents of said hopper, means for rotating said belt, said hopper having a discharge gate on one side of the lower portion thereof, a support plate positioned immediately below the top portion of said belt, said plate being positioned directly below the lower end of said hopper, and means for vibrating said plate associated therewith, said plate being adapted to transmit vibrations to the material stored in said hopper.

5. A continuous dispenser device for granular

material comprising a hopper for storing a quantity of the material, said hopper having an open lower end, an endless belt, means journaling said belt with the top portion thereof being immediately below but spaced from the lower end of said hopper to support the contents of said hopper, means for rotating said belt, a support plate positioned immediately below the top portion of said belt directly below the lower end of said hopper, and means for vibrating said plate, said plate being adapted to transmit vibrations through the said belt to the material stored in said hopper.

6. A continuous dispenser device for granular material comprising a hopper for storing a quantity of the material, said hopper having an open lower end, a belt, means positioning said belt with a top portion thereof below the lower end of said hopper to receive and at least partially support the contents of said hopper, a support member positioned immediately below said belt directly below the lower end of said hopper, and means for vibrating said support member whereby vibrations are transmitted to the material stored in said hopper.

7. That method of feeding aggregates the volume of which differs with the moisture content of the aggregates comprising the steps of collecting a quantity of an aggregate, vibrating the entire quantity of such aggregate while maintained in a mass to densify same and render the volume thereof uniform regardless of the moisture content of same, retaining the aggregate in the vibrated mass until a constant volume of aggregate is obtained, and volumetrically discharging the constant volume aggregate at a uniform dry weight rate due to the uniform volume thereof.

8. That method of feeding an aggregate the volume of which differs with the moisture content of same, comprising the steps of collecting a quantity of an aggregate, vibrating the entire quantity of such aggregate while maintained in a mass to densify same and render the volume thereof uniform regardless of the moisture content of same, retaining the aggregate in the vibrated mass until a constant volume of aggregate is obtained, and continuously discharging the constant volume aggregate by a controlled volume discharge thereof.

9. A method of concentrating a material such as sand, cinders, or blast furnace slag comprising the steps of continuously feeding the material to a storage area, vibrating the material in the storage area primarily in a vertical direction, and continuously withdrawing a portion of the material from the storage area from the lowest portion thereof, which withdrawal is volumetrically controlled and with the material being retained in the storage area for sufficient time to be reduced to minimum volume prior to discharge from such area.

10. A method of concentrating and feeding a material primarily comprising sand, cinders, or blast furnace slag the volume of which differs with the moisture content of same comprising the steps of feeding the material to a storage area to maintain a volume of material therein, vibrating the material in the storage area in substantially only a vertical direction until the material in at least the lower portion thereof is of uniform volume regardless of the moisture content of same, and controlling the volume of a discharge opening for the storage area in the

lowest portion thereof to discharge desired weights of material by control of the volumes discharged.
